VENETIAN BLIND

Jesse E. Cooper, Los Angeles, Calif., assignor, by
mesne assignments, to National Venetian Blind
Co., Los Angeles, Calif., a corporation of Cali-
fornia

Application July 19, 1934, Serial No. 735,924

5 Clairs. (Cl. 156—17)

The present invention relates to Venetian blinds, and more particularly to the construction of and the co-operative association between the head-rails and the tilt-rails of blinds of the general class indicated.

It is common practice in the construction of Venetian blinds, to suspend the slats of a blind from a tilt-rail which in turn is supported below a head-rail or other member which usually serves as the means whereby the blind is mounted in operative position. The slats are supported through the expedient of opposed tapes engaging the front and rear edges of the slats and secured respectively to the front and rear edges of the tilt-rail which is so mounted that it is subject to being tilted, whereby all the slats are simultaneously tilted so as to vary the amount of air and/or light permitted to pass between the several slats of the blind. In the usual construction of head-rail and tilt-rail, however, sufficient space has been left between these two members to permit the latter to be swung into a substantially vertical plane in order close the blind and thereby prevent substantially all passage of air and/or light between the slats. Due to the mechanical requirements which must be met in order to permit free movement of the parts at all times, it has been necessary to mount the tilt-rail far enough below the head-rail to have a material degree of clearance therebetween even when the tilt-rail is in its fully closed position. In usual practice, the clearance amounts to as much as three eighths or a half an inch. This practice has proven to be objectionable in many instances, because it permits leakage of a streak of light of that thickness and extending throughout the width of the blind, this leakage being present, and, in fact, particularly objectionable, when the blind is in fully closed position, for it is due to the darkened condition of the room or other enclosure where the blind is installed that the streak of light referred to is more noticeable. Although the other parts of the blind are in fully closed position, preventing passage of substantially all light between the slats, it is never possible, with Venetian blinds of conventional construction, to intercept this annoying and often highly objectionable streak of light at the top of the blind.

An object of the present invention, therefore, is to provide a Venetian blind, wherein means are provided for intercepting and dispensing with the streak of light which, in more conventional Venetian blinds, leaks between the head-rail and tilt-rail even when the blind is fully closed.

Another object is to provide a novel type of head-rail and tilt-rail construction having means for preventing leakage of light therebetween, which, to the casual observer, has the same appearance as the usual type of construction, which performs all the functions of the ordinary type fully as well, and the cost of manufacture, assembly or installation of which is no greater.

The invention possesses other objects and valuable features, some of which, with the foregoing, will be set forth in the following description of the invention's preferred embodiments which are illustrated in the drawing accompanying and forming a part of this specification. It is to be understood that I do not limit myself to the showing made by the said drawing and description, as I may adapt variations of the preferred forms within the scope of the invention as set forth in the claims.

Referring to the drawing:

Figure 1 is a transverse, vertical sectional view taken through the upper portion of a Venetian blind embodying the principle of the present invention, with the tilt-rail in horizontal, or fully open position.

Fig. 2 is a view similar to Fig. 1, but with the tilt-rail and slats moved toward closing position.

Fig. 3 is another view similar to Fig. 1, but showing a slightly modified form of construction.

Fig. 4 is still another view similar to Fig. 1, but showing a further modified form of construction.

In terms of broad inclusion, the present invention contemplates the mounting of the tilt-rail of a Venetian blind at a less space below the head-rail or other member below which it is pivoted, as compared with more conventional constructions, so that when the tilt-rail is swung to a substantially vertical plane, thereby closing the blind, an edge of the tilt-rail enters a recess in the under surface of the head-rail or its equivalent, thereby serving effectually to establish a substantially light-tight seal between the tilt-rail and the member immediately thereabove.

More specifically described, the Venetian blind of my present invention comprises a head-rail 6 below which is pivotally mounted, as by supporting brackets 7, a tilt-rail 8. At predetermined intervals throughout the length of the tilt-rail 8, opposed tapes 9 hang from opposite edges of the tilt-rail 8, these tapes serving to support a plurality of slats 11 in the conventional manner. The association between the tilt-rail and the several slats 11, (only one of which is shown in the drawing) is such that the slats 11 are subject to being adjusted simultaneously from horizontal planes 55

to inclined or even substantially vertical planes by similar movement of the tilt-rail 8, it being understood that the tilt-rail 8 is supported by the brackets 7 or their equivalent for movement about an axis 12, extending longitudinally of the tilt-rail 8. Whereas any suitable means for effecting adjustment of the tilt-rail 8 may be employed, the mechanism which has been chosen for illustration comprises a substantially semi-circular worm wheel 16 fixed preferably at one end of the tilt-rail 8 in coaxial relationship thereto. This worm wheel 16 is enmeshed with a driving worm 17 carried by a shaft 18 which is journaled preferably in one of the brackets 7 and which extends transversely of the head-rail 6 beyond the reveal or inner face 19 thereof where it carries a sheave (concealed under a hood 21) over which passes a cord 22 which may be manipulated from below to effect rotation of the shaft 18 and worm 17 whereby rotational adjustment of the worm wheel 16 and tilt-rail 8 can be effected.

Elevation of the lowermost slat and gathering thereon of the slats 11 thereabove can be effected in the usual manner through the expedient of additional cords 23 which depend from the head-rail 6 passing through the tilt-rail 8 and the slats 11 in a manner well known in the art to which this invention pertains.

Observation of Figures 1 and 2 will reveal that a recess 26 is made in the under surface 27 of the head-rail 6 with a lip or apron 28 extending downwards at each of the inner and outer edges 19 and 29 respectively of the head-rail 6. Furthermore, the brackets 7 are of such length and they are so positioned that an edge (say the inner edge 31) of the tilt-rail 8 enters the recess 26 when the tilt-rail is tilted so as to move that edge 31 upwards. This is the principal point of differentiation of the blind of my invention and those constructed along more conventional lines. The axis 12 about which the tilt-rail 8 moves is disposed at a less distance below the mouth of the recess 26 than the radius of the greatest circular arc described by a portion of the tilt-rail 8 when the latter swings.

As will be clearly understood by observation of Figure 2, this arrangement of the tilt-rail 8 with respect to the head-rail 6 results in intercepting the streak of light which would otherwise penetrate between these two members even when the tilt-rail 8 is tilted to its most nearly fully closed position, thereby representing a material improvement over more conventionally constructed Venetian blinds wherein sufficient space must be left between the head-rail and tilt-rail to leave a material clearance between the members even when the tilt-rail is in its most nearly vertical position, which arrangement, as explained hereinabove, permits penetration of an objectionable streak of light into the room or other enclosure where the blind is installed, such penetration taking place even when the blind is otherwise completely closed and being at such times most objectionable because the leakage of this streak of light is most noticeable when the room is nearly darkened as the result of the closing of the major portion of the blind.

Fig. 3 shows a slightly modified form of construction wherein the recess 26' in the under surface 27' of the head-rail 6 is narrower than the recess 26 of the first described modification. Here the recess 26' is of arcuate cross-sectional configuration, the center of the arc described thereby lying substantially within the axis 12' about

which the tilt-rail 8' swings. However, as in the first described modification, whichever edge, say the edge 31', of the tilt-rail moves upwards is caused to enter the recess 26' and thereby effect a substantially light-tight seal between the head-rail 6' and tilt-rail 8' when the blind is closed.

Fig. 4 discloses another modified form wherein the recess 26'' in the under surface 27'' and the head-rail 6'' is defined by but a single lip or apron 28'' extending along preferably the outer surface 10 29'' of the head-rail 6''.

Whereas the lips or aprons 28, 28', or 28'', as the case might be, defining the recess 26, 26', and 26'' respectively, have been illustrated as being composed of the same material as that of which the head-rail proper is composed, it should be understood that they may be made separately from the head-rail and attached thereto by any convenient means, the only requirement in so far as the present invention is concerned being that they extend far enough below the horizontal plane reached by an edge of the tilt-rail when in the most nearly vertical position of the latter to intercept light which would otherwise tend to leak between the tilt-rail and the member from which the apron or aprons, as the case might be, depend.

I claim:

1. In a Venetian blind, a tilt-rail adapted to support slats of a blind for tilting adjustment, and means supporting said tilt-rail for tilting movement, said supporting means having a recess in the under surface thereof, and the axis of movement of said tilt-rail being spaced from the mouth of said recess less than the distance between said axis and an edge of said tilt-rail.

2. In a Venetian blind, a tilt-rail adapted to support slats of a blind for tilting adjustment, a horizontal member having a recess in the under surface thereof, and means for supporting said tilt-rail under said horizontal member for tilting movement, the axis of movement of said tilt-rail being spaced from the mouth of said recess less than the distance between said axis and an edge of said tilt-rail.

3. In a Venetian blind, a head-rail having a recess in the under surface thereof, and a tilt rail tiltably mounted therebelow, the axis of tilting movement of said tilt-rail being spaced from the mouth of said recess less than the distance between said axis and an edge of said tilt-rail where by said edge is caused to enter said recess when said tilt-rail is tilted, with said edge toward said head-rail.

4. In a Venetian blind, a head-rail, a plurality of blind slats and means supporting said slats below said head-rail for tilting adjustment whereby said slats can optionally be positioned in spaced, substantially horizontal planes or in overlapping, closely adjacent relationship to intercept light rays, said supporting means being disposed in position to overlap a portion of said head-rail when said slats are in light-intercepting position and thereby establish a substantially light-tight seal between said slats and said head-rail.

5. In a Venetian blind, a supporting member, a tilt-rail pivotally mounted for tilting adjustment below said supporting member, and means on said supporting member extending downwards beyond the highest plane reached by an edge of said tilt-rail when tilted for intercepting light rays which would otherwise pass between said supporting member and said tilt-rail.

JESSE E. COOPER.
